UNITED STATES PATENT OFFICE.

FRANK W. EDWARDS, OF BAYONNE, NEW JERSEY.

BOILER-TUBE CLEANER.

SPECIFICATION forming part of Letters Patent No. 595,908, dated December 21, 1897.

Application filed April 24, 1897. Serial No. 633,652. (No model.)

To all whom it may concern:

Be it known that I, FRANK W. EDWARDS, of Bayonne, Hudson county, State of New Jersey, have invented an Improvement in 5 Boiler-Tube Cleaners, of which the following is a specification.

My invention has reference to boiler-tube cleaners; and it consists of certain improvements, which are fully set forth in the following specification and shown in the accompanying drawings, which form a part thereof.

The object of my invention is to provide a suitable construction of boiler-tube cleaners which shall employ a head adapted to be moved slowly through the tube and guided thereby, combined with a rapidly-vibrating hammer operated by steam or air pressure which shall have a capacity of delivering blows in rapid succession upon the interior 20 walls of the tube, whereby the scale or deposit upon the interior shall be detached and at the same time scale or incrustation upon the outside of the tube shall be loosened and removed, due to the concussion of the hammer 25 upon the tube.

In carrying out my invention I employ a head composed of a solid casting having fitted thereto a pivoted hammer, combined with a transversely-operating piston arranged to 30 directly vibrate the hammer and an automatic valve to control the movement of the piston, the said cylinder and piston being inclosed by a sheath or casing, forming the outer wall of the head and held in place by a 35 suitable cap.

Furthermore, my improved tube-cleaner is provided with ports directed toward the front, so as to deliver the escaping steam or air toward the hammer to blow before the cleaner 40 all the loosened scale or deposits and thereby avoid binding or clogging of the cleaner within the tube and also to insure the hammer operating upon undetached portions of the scale and not upon accumulations which 45 might fall in the vicinity of the hammer or be pushed along under the action of the head in its forward movement. In this manner the hammer operates with the greatest effect and with the most rapid results. The head 50 is connected to the end of the hollow rod or tube, into which steam or air is forced under

pressure, and by which tubular rod the position of the head within the boiler-tube is also definitely secured. During the forward movement of the cleaner through the tube it 55 is slowly revolved, so that the hammer is enabled to operate upon every portion thereof. A boiler-tube cleaner of this character has an advantage over the ordinary scraper-cleaners in that it cleans both the inside and outside 60 of the tubes, performs its work more rapidly and perfectly, and if there is a weakness in any tube which might, under the pressure of the boiler after cleaning, be liable to burst or leak said weakness is readily detected by 65 the action of the hammer, or brought to such condition that immediately upon putting the smallest pressure in the boiler the defect is made apparent before serious damage is done.

A feature which is of the greatest importance in connection with the construction herein set out is that in all steam-actuated concussion-cleaners which I have heretofore had occasion to use the parts were so constructed as to quickly become worn out, the 75 defect from this cause frequently permitting a life of only a few hours. My improved construction has been specially designed with the object of securing the greatest possible life to a machine of this character, and the 80 practical experience with the said machine shows it to have the desirable requisites of durability and proof against objectionable lost motion and of getting out of repair.

My invention will be better understood by 85 reference to the accompanying drawings, in which—

Figure 1 is a plan view of my improved boiler-tube cleaner with a portion of the head cut away. Fig. 2 is a longitudinal sectional 90 elevation of same on line xx of Fig. 1. Fig. 3 is a perspective view of the casing and cap removed. Fig. 4 is a perspective view of the complete boiler-tube cleaner with the said casing and cap disconnected, and Figs. 5 and 95 6 are views corresponding to Figs. 1 and 2 with modifications.

A is a solid cylindrical casting provided at one end with a flange A' and at the other end with a deep transverse notch or aperture B 100 and a screw-threaded end b. Fitted to the rear end of this casting A is a tubular rod L,

through which the steam or air is supplied for operating the cleaner. Encircling the casting A is a tubular sleeve or casing C, and this is held in place by means of the flange A' 5 at one end and the cap D, which is secured upon the screw-threaded end b of the casting A at the other end. The cap D is provided with an aperture d through its end, in which the shank of the hammer E operates. The 10 hammer E is pivoted in the end B of the casting A upon a pin F, and the free end extends through the cap D and is provided with the hammer-head E', which may be circular in form, and also furnished, if desired, with 15 knife or serrated edges e around its forward edge, the object of which is to subdivide or cut off projecting portions of the scale immediately in the plane and path of the hammer, so as to more readily loosen and disintegrate it. If desired, these knife edges or 20 serrations may only be upon those portions of the hammer-head which are in the direct plane of the blow. The rear end of the hammer E is provided with an extension or arm 25 E², which fits into a notch or slot H' on a transversely-reciprocating piston H. This piston may consist of a solid cylindrical block and formed with a transverse slot H', before referred to, for receiving the arm of the 30 hammer. The piston snugly fits a cylinder-casing G, which is forced into a transverse cylindrical aperture through the casting A. The piston does not require any packing, as the 35 question of leakage is of no special importance except to insure the proper working of the valve-ports.

By employing the removable cylinder-casing G it is evident that when the same becomes worn it may readily be removed and a 40 new casing inserted. The same is also true of the piston. Arranged parallel to the cylinder and piston is an automatic piston-valve J, which controls the steam from the tubular rod L in its passage into the ends of the cylinder. As shown, the steam passes by the 45 valve-cylinder I, through the port k, into the cylinder G at one end of the piston, while the expended steam escapes from the other end of the cylinder through corresponding ports 50 k into the exhaust-port K, which surrounds the cylinder-casing G, and is directed to the forward end of the casting, so as to open into the slot B, with the object that the escaping steam shall find a passage toward the hammer 55 for the purpose of blowing away any detached scale. To reciprocate the valve J, I provide a port h in the piston H and two ports i, leading to opposite sides of the valve and with which the port h alternately connects. The 60 valve J is also provided with small ports j at each end for the purpose of allowing steam to pass to the opposite end of the valve for reciprocating the valve as an entirety.

Referring to Fig. 2, it will be observed that 65 as the piston H descends the ports h will ultimately arrive in line with the port i. When this takes place, the steam which passes

through the lower port j in the valve finds a ready escape through the ports i h and the transverse slot E³ in the arm E² of the hammer, while the steam passing through the ports j of the valve has no outlet or relief and instantly raises the valve. This produces a reverse movement of the piston H and ultimately a reverse movement of the valve, said 70 actions taking place with great rapidity, the speed of which is practically limited by the rate of vibration of the hammer E, acting as a pendulum. The ends of the valve-cylinder and of the piston-cylinder are positively 75 closed by the cylinder-casing C, which is fitted over the casting A. Broadly considered, the particular construction of the valve is immaterial to my invention, though it should be automatic, and the construction shown is 80 most durable and excellently adapted to the purpose.

As the tubes to be cleaned vary in size, it is desirable to provide means to adapt the head to such different sizes to avoid the necessity of an excessive number of sizes of tube-cleaners. This is secured by placing an annular ring c between the flange A' and the tubular casing C, the said ring being of a diameter substantial to fit the interior of the 95 tube and thus centralize the head and the hammer. Furthermore, it reduces the friction and labor of moving the head to a minimum. It is simply necessary to place a ring 100 of different diameter upon the head to suit the requirements of different diameters of tubes; but it will be understood that this method of adapting the cleaner to different-sized tubes is limited by the possible throw or 105 vibration of the hammer.

As it is important to cause a quick relief of the exhaust-steam when the impetus to the hammer is secured, I prefer to provide outlet-ports R directly through the cylinder-casing G into the exhaust-ports K. When 110 to the hammer is given the momentum, it will of necessity cause the piston to continue its throw to secure the necessary operation of the valve J, and as the rapidity of movement is so great the passage of live steam 115 through said ports is not objectionable, since it is not excessive and what does pass is fully utilized in the blast which is utilized to move the detached scale or material within the tube.

To further assist the hammer in detaching 120 and clearing the scale from the interior of the tube, I prefer to employ longitudinal bypasses m, M, and M' in the casting A and cap D. (More clearly shown in Figs. 1, 3, and 4.) These by-passes consist of ports m, leading 125 from the steam-supply chamber l, longitudinal channels or ports M, formed in the periphery of the casting A and inclosed by the casing G, so as to be readily cleaned when desired, and the oblique ports or nozzles M' 130 through the head and directed obliquely for the purpose of causing a rotary action to the blast, so as to act upon the scale immediately in front of the points where the hammer is

to operate, whereby it is enabled at all times to act upon, detach, and move forward all portions of the loosened scale.

Referring now more particularly to Figs. 5 and 6, I have shown some details not embodied in the construction of my invention shown in Figs. 1 and 2. While the general construction is the same in both cases, I have provided the valve J with a removable cylinder J', corresponding to the removable cylinder G for the piston H, whereby it may be replaced when worn and keep the valve in good working condition. The wear on the valve comes mainly from the great vibration imparted to the apparatus by the blows of the hammer, which fall at the rate of about two thousand per minute, while the valve is performing the same number of reciprocations. I have also shown the head E' of the hammer removable and adjustable. As shown, it is fitted upon a tapered end of the hammer-arm E and held in place by a clamping-screw E². By this means the head may be adjusted to bring new portions into action when the former portions in action become worn, and, finally, a new head may be substituted, if desired, and the heads may be replaced by others shaped to suit the particular work to be performed.

Another feature of improvement shown in Figs. 5 and 6 is that the piston H is provided with port-section T, of hardened steel, which is pressed against the interior of the cylinder by the springs t, so as to make the port h, which controls the valve movement, operate without excessive leakage even when the piston H is worn by use. The remaining features of Figs. 5 and 6 are in all material respects similar to those of Figs. 1 to 4.

While I prefer the construction shown, I do not limit myself to the minor details, as they may be modified in various ways without departing from the principles of my invention.

Having now described my invention, what I claim as new, and desire to secure by Letters Patent, is—

1. In a boiler-tube cleaner, a head attached to the end of a tubular rod or blast-pipe combined with a pivoted vibrating hammer, pivoted to the head and having a rear end beyond the pivot, a transversely-reciprocating piston having a slot extending only part way through the piston into which the rear end of the hammer projects and by which it is operated, and an automatic valve for controlling the supply of steam or air to either end of the piston.

2. In a boiler-tube cleaner, a head attached to the end of a tubular rod or blast-pipe, combined with a pivoted vibrating hammer pivoted to the head and having a rear end beyond the pivot, a transversely-reciprocating piston having a slot extending only part way through the piston into which the rear end of the hammer projects and by which it is operated, an automatic valve for controlling the

supply of steam or air to either end of the piston, and blast-ports leading from the cylinder to the forward part of the head so as to direct a strong forward current of steam or air to clear the tube.

3. In a boiler-tube cleaner, a head attached to the end of a tubular rod or blast-pipe, combined with a pivoted vibrating hammer pivoted to the head and having a rear end beyond the pivot, a transversely-reciprocating piston having a slot extending only part way through the piston into which the rear end of the hammer projects and by which it is operated, an automatic valve for controlling the supply of steam or air to either end of the piston, and obliquely-directed passageways M' for directing steam or air under pressure through the forward end of the head so as to act upon the scale in the tube substantially in line with the action of the vibrating hammer and causing it to assume a spiral motion.

4. In a boiler-tube cleaner, a head attached to the end of a tubular rod or blast-pipe, combined with a pivoted vibrating hammer pivoted to the head and having a rear end beyond the pivot, a transversely-reciprocating piston having a slot extending only part way through the piston into which the rear end of the hammer projects and by which it is operated, a removable cylinder or casing for the piston arranged transversely through the head and having a large central opening 100 through which the hammer extends to make connection with the piston.

5. In a boiler-tube cleaner, the combination of a cylindrical casting having a recessed or slotted end and a transverse cylinder, a sleeve 105 or casing fitting over the said casting so as to form the heads of the cylinder, a detachable cap securely fastened to the forward end of the cylindrical casting and having an aperture through which the hammer operates, 110 a vibrating hammer pivoted in the slotted end of the head upon an axis transverse to the cylinder and having a rearwardly-extending arm extending into and terminating in the body of the cylinder, a reciprocating piston 115 fitted to said cylinder and having a transverse slot for receiving the rear arm of the hammer, an automatic valve for controlling the supply of steam to either end of the cylinder, and a tubular rod secured to the rear 120 end of the cleaner for supplying steam or air under pressure to the valve and cylinder.

6. In a boiler-tube cleaner, the combination of a cylindrical casting having a recessed or slotted end and a transverse cylinder, a sleeve 125 or casing fitting over the said casting so as to form the heads of the cylinder, a detachable cap securely fastened to the forward end of the cylindrical casting and having an aperture through which the hammer operates, 130 a vibrating hammer pivoted in the slotted end of the head upon an axis transversely to the cylinder and having a rearwardly-extending arm extending into and terminating in

the body of the cylinder, a reciprocating piston fitted to said cylinder and having a transverse slot for receiving the rear arm of the hammer, an automatic valve for controlling the supply of steam to either end of the cylinder, a tubular rod secured to the rear end of the cleaner for supplying steam or air under pressure to the valve, and exhaust-ports leading from the cylinder to the forward part 10 of the cylindrical casting so as to project a blast of steam or air in the direction of the vibrating hammer.

7. In a boiler-tube cleaner, the combination of a cylindrical casting having a transverse cylinder, a sleeve or casing fitting over the said casting so as to form the heads of the cylinder, a detachable cap securely fastened to the forward end of the cylindrical casting and having an aperture through which the hammer operates, a vibrating hammer pivoted upon an axis transversely to the cylinder and having a rearwardly-extending arm extending into the body of the cylinder, a reciprocating piston fitted to said cylinder and having a transverse slot for receiving the arm of the hammer, an automatic valve for controlling the supply of steam to either end of the cylinder, a tubular rod secured to the rear end of the cleaner for supplying steam or air under pressure to the valve and cylinder, exhaust-ports leading from the cylinder to the forward part of the cylindrical casting so as to project a blast of steam or air in the direction of the vibrating hammer, and bypasses for steam or air extending from the steam or air ports to the forward end of the cap and directed obliquely to the end of the cap whereby a rotary action is secured to the steam or air at the forward end of the cleaner 40 and adjacent to the hammer-head.

8. In a boiler-tube cleaner, the combination of a cylindrical casting or head having a transverse cylinder detachably secured in a transverse aperture through the cylindrical casting, a sleeve or casing fitting over the said casting so as to form the heads of the cylinder, a detachable cap securely fastened to the forward end of the cylindrical casting or head to hold the sleeve in place and having an aperture through which the hammer operates, a vibrating hammer pivoted in the head upon an axis transversely to the cylinder and having a rearwardly-extending arm projecting through the cylindrical casting and the middle portion of the wall of the cylinder and into and terminating in the interior thereof, a reciprocating piston fitted to said cylinder and having a slot on one side for receiving the arm of the hammer, an automatic valve for controlling the supply of steam to either end of the cylinder, and a tubular rod secured to the rear end of the cleaner for supplying steam or air under pressure to the valve.

65 9. In a boiler-tube cleaner, a head attached to the end of a tubular rod or blast-pipe, combined with a pivoted vibrating hammer hav-

ing a free rear extension, a transversely-reciprocating piston having a slot into which the rear extension of the hammer projects 70 and by which it is operated so that the hammer-head and piston simultaneously move in opposite directions, an automatic valve for controlling the supply of steam or air to either end of the piston, and relief exhaust-ports 75 opening through the cylinder near each end and opened and closed by the movement of the piston to permit the escape of steam from the cylinder after a given portion of the stroke has been secured.

10. In a boiler-tube cleaner, the combination of a suitable head, a vibrating hammer provided with an enlarged head having a smooth hammer portion to deliver the blow, and an oblique knife or serrated portion immediately 85 in the front for operating upon the scale adjacent to that upon which the blow is delivered, and power mechanism contained within the head for vibrating the hammer.

11. In a boiler-tube cleaner, the combination 90 of a suitable cleaner-head secured to the end of a tubular rod or blast-pipe, a vibrating hammer-arm pivoted to the head, a removable hammer-head adjustably secured to the arm and having an annular smooth part and an 95 annular serrated or cutting part, and power mechanism contained within the cleaner-head for vibrating the hammer-arm.

12. In a boiler-tube cleaner, a head attached to one end of a tubular rod or blast-pipe, in 100 combination with a transversely-reciprocating piston movable in the head, a vibrating hammer pivoted intermediate of its ends in the head between the piston and forward end of the head and having a direct loose connection 105 with the piston, and a valve independent of the hammer controlled by the movements of the piston for governing its reciprocation.

13. In a boiler-tube cleaner, a head attached to one end of a tubular rod or blast-pipe and 110 open at its end, in combination with a transversely-reciprocating piston having a recess in one side adjacent to the open end of the head, a vibrating hammer extending through the open end of the head and pivoted thereto between the piston and end of the head, a mechanical connection between the hammer and recess in the piston whereby the latter vibrates the hammer, and an automatic valve 120 to control the supply of steam or air to either 125 end of the piston consisting of a reciprocating cylindrical valve moved by a difference in pressure of steam on opposite faces, and a relief - port extending transversely through the reciprocating piston for reducing the pressure on either side of the valve to cause its 130 automatic reciprocation with a speed commensurate with that of the piston.

14. In a boiler-tube cleaner, a head attached to one end of a tubular rod or blast-pipe, in 130 combination with a pivoted vibrating hammer, a transversely-reciprocating piston having a mechanical connection with the hammer to vibrate it, and an automatic valve to

- control the supply of steam or air to either end of the piston consisting of a reciprocating cylindrical valve moved by a difference in pressure of steam on opposite faces, a spring-
5 pressed plate moving with the piston and provided with a relief-port for reducing the pressure on either side of the valve to cause its automatic reciprocation with a speed commensurate with that of the piston.
- 10 15. In a boiler-tube cleaner, a head attached to the tubular rod or blast-pipe provided with a pivoted vibrating hammer, a transversely-reciprocating piston for operating said hammer arranged within the head, an automatic reciprocating cylindrical valve for controlling the supply of steam to either end of the piston, and a removable valve-casing having a central transverse perforated diaphragm fitted transversely through the head and having ports communicating with the cylinder in which the reciprocating piston operates and also with the tubular rod or blast-pipe, the diaphragm receiving the end thrusts or blows of the valve in its rapid reciprocation.

16. In a boiler-tube cleaner, the combination 25 of a head secured to the end of a tubular rod or blast-pipe, a hammer pivoted in the head and adapted to vibrate, a transverse cylinder formed in the head, a reciprocating piston for operating the vibrating hammer and provided 30 with a relief-port *h*, a valve-chamber *I*, a reciprocating cylindrical valve *J* movable therein and controlling the steam or air through the ports *K* *k* to or from the main cylinder, means to supply live steam to opposite ends 35 of the cylindrical valve, and relief-ports *i* from the valve-chamber the escape of steam through which is controlled by the relief-port *h* of the piston to relieve the pressure of the steam on portions of the valve to cause the 40 said valve to reciprocate.

In testimony of which invention I hereunto set my hand.

FRANK W. EDWARDS.
